UNITED STATES PATENT OFFICE.

AUGUSTE CAMILLE EDMOND RATEAU, OF PARIS, FRANCE, ASSIGNOR TO RATEAU TURBINE COMPANY, OF CHICAGO, ILLINOIS, A CORPORATION OF WEST VIRGINIA.

AUTOMATIC REGULATING DEVICE FOR FLUID-PRESSURE APPARATUS.

No. 902,001.

Specification of Letters Patent.

Patented Oct. 27, 1908.

Application filed April 28, 1905. Serial No. 257,849.

To all whom it may concern:

Be it known that I, AUGUSTE CAMILLE EDMOND RATEAU, a citizen of the Republic of France, residing at Paris, France, have invented certain new and useful Improvements in Automatic Regulating Devices for Fluid-Pressure Apparatus, for which I have obtained Letters Patent in foreign countries as follows: France, No. 342,896, May 5, 1904; 5 Belgium, No. 147,358, April 10, 1905, and Switzerland, April 10, 1905, and of which the following is a specification.

The present invention has for its object a plan of automatic regulation of fluid pressure apparatus, being designed more particularly as a system of regulation for pumps serving to feed boilers.

In its particular intended application the invention is employed in connection with 15 centrifugal pumps used for feeding boilers.

Centrifugal pumps having a large head can be utilized for feeding steam boilers, even to pressures as high as about three hundred pounds per square inch. In contradistinction to the operation of reciprocating pumps, 25 centrifugal pumps offer the advantage that at a velocity of rotation which is substantially constant they can yield a very variable output of water, but it is necessary to employ a special system of regulation which obliges 30 the steam motor driving the centrifugal pump to give an amount of work proportional to the required flow. It is also necessary that in case the pump loses its priming 35 through the flow becoming interrupted on account of the entrance of air, or for other reasons, the racing of the motor should be prevented. This double condition is realized by the system of regulation forming the 40 subject of the present invention, and which, in a preferred mechanical form, is shown in the accompanying drawing, wherein,—

Figure 1 is a vertical sectional view showing the construction and arrangement of the 45 regulator; and Fig. 2 is a diagrammatic view illustrating the various connections between the boiler, pump and motor.

Referring to the drawings, 1 designates the throttle-valve of the motor, herein diagrammatically shown as a steam turbine. 50 This throttle-valve is secured to the stem 2, and by moving down more or less it partially cuts off the admission of steam to the motor. 3 designates a lever having a pivot 55 al axis at 4 on a suitably mounted stem

15^a, and engaging the lower end of the stem 2. This lever 3 is acted upon at its extremity 5 by the connected differential pistons 6 and 7 operating in a casing 6^a. The diameter of the piston 6, through which the pressure of the boiler 9 acts by means of a connecting pipe 8, is a little greater than that of the piston 7, which latter is subjected, through a pipe 10, to the pressure of the water discharged by the centrifugal pump 11. 60 By means of these differential pistons, which are in equilibrium when the pressure of the water discharged by the pump 11 is a little higher than the pressure of the steam, the lever 3 will move the throttle-valve to admit 65 steam to the motor 12 of the pump when the pressure of the water tends to fall; and, on the contrary, will throttle the admission of steam when the pressure of the water tends to rise above a point which is found to be in 70 normal or constant relation to the pressure of the steam. Furthermore, the lever 3 is acted upon by a spring 13, the tension of which can be varied by means of a hand wheel 14. This spring permits any desired 75 variation or regulation of the constant relation between the pressure of the water delivered by the pump 11 and that of the steam in the generator 9.

The pivot of the lever 3 is, as already 80 stated, mounted on the rod 15^a which forms the stem of a piston 15, the lower face of which is in communication, through the pipe 16, with the discharge pressure of the pump 11. When this pressure is sufficiently high 85 this piston 15 raises the pivot 4 and maintains it in its normal position; but should the pressure of the water discharged by the pump 11 fall materially or cease altogether 90 by reason of the pump losing its priming, or for any other reason, the pressure of water on the piston 15 falls, and a counteracting spring 17 thrusts the piston and the pivot 4 downwardly. The throttle-valve 1 is then 95 closed and the motor stops, whatever may be 100 the position of the differential pistons 6 and 7.

To again start the machine, all that is necessary is to raise the axis 4 by elevating the lever 3 by hand, for which purposes the latter is provided with a handle 18. The lever 3 105 is held up until the normal speed is attained, and at this instant, if the pump is operating normally, the lever can be released, the pressure below the piston 15 being sufficient to offset the spring 17 and maintain the pivot 4 110

in its normal position. It will thus be seen that by the simple arrangement of mechanism described this double result is obtained, viz: that the pressure of discharge of the 5 pump 11 is always higher than the pressure of the steam in the boiler, and that the apparatus automatically stops as soon as the entrance of air or the failure of priming interrupts the continuity of flow of the centrifugal 10 pump.

It will be understood that the specific constructions herein illustrated of the several parts are typical only, and may take on any of the usual and well known forms.

15 I claim:

1. The combination with a pressure generator, of a motor, a connection for applying pressure from said generator to said motor, a regulator for controlling the pressure admitted to said motor, a pump driven by said motor, and controlling mechanism independent of the regulator for governing said regulator, said controlling mechanism being acted upon oppositely by the pressure from said 25 generator and said pump.

2. The combination with a pressure generator, of a motor, a pump for supplying said generator driven by said motor, a regulator for said motor having a movable controlling 30 part, and controlling mechanism for governing said regulator, said controlling mechanism comprising differential pistons of unequal cross-section acted upon oppositely by the pressure from said generator and said 35 pump, respectively.

3. The combination with a fluid feed pump, of a motor driving the same, and mechanism controlling said motor adapted to shut off the power thereto when the fluid 40 pressure from said pump fails, substantially as described.

4. The combination with a fluid feed pump, of a motor driving the same, and a mechanism subjected to the discharge pressure 45 of the pump controlling said motor and adapted to shut off the power thereto when the fluid pressure from said pump fails, substantially as described.

5. The combination with a fluid pressure generator, of a motor receiving its motive 50 fluid supply from said generator, a pump for supplying said generator driven by said motor, a throttle-valve for said motor, and a differential - piston controlling mechanism 55 connected to said throttle-valve, but independent thereof, the pistons whereof are acted upon oppositely by the pressure from said generator and said pump, respectively, substantially as described.

60 6. The combination with a fluid pressure generator, of a motor, a pump for supplying said generator driven by said motor, a throttle-valve for said motor, a pair of connected differential pistons exposed respectively to op- 65 positely acting pressures from said generator

and said pump, and a lever connecting said pistons and the stem of said throttle-valve, substantially as described.

7. The combination with a fluid pressure generator, of a motor, a pump for supplying 70 said generator driven by said motor, a throttle-valve for said motor, a pair of connected differential pistons exposed respectively to oppositely acting pressures from said generator and said pump, a lever connecting said 75 pistons and the stem of said throttle-valve, and means regulated by the pressure from said pump serving to vary the position of the fulcrum point of said lever, substantially as described.

8. The combination with a fluid pressure generator, of a motor, a pump for supplying said generator driven by said motor, a throttle-valve for said motor, a pair of connected differential pistons exposed respectively to oppositely acting pressures from said generator and said pump, a lever connecting said pistons and the stem of said 85 throttle-valve, and a piston on which said lever is fulcrumed, said last-named piston 90 being exposed to the pressure from said pump, substantially as described.

9. The combination with a fluid pressure generator, of a motor, a pump for supplying said generator driven by said motor, a throttle-valve for said motor, a pair of connected differential pistons exposed respectively to oppositely acting pressures from said generator and said pump, a lever connecting said pistons and the stem of said throttle-valve, a 95 piston exposed to the pressure from said 100 pump and pivotally supporting said lever, and a spring acting upon the pivot of said lever in opposition to said last-named piston, substantially as described.

10. The combination with a fluid pressure generator, of a motor, a pump for supplying said generator driven by said motor, a throttle-valve for said motor, a pair of connected differential pistons exposed respectively to 110 oppositely acting pressures from said generator and said pump, a lever connecting said pistons and the stem of said throttle-valve, an adjustable spring acting upon one arm of 115 said lever, a piston exposed to the pressure from said pump and pivotally supporting said lever, and a spring acting upon the pivot of said lever in opposition to said last-named piston, substantially as described.

11. The combination with a steam boiler, of a steam engine, a centrifugal pump for supplying feed water to said boiler driven by said engine, a throttle-valve for said engine, a pair of connected differential pistons exposed respectively to the steam pressure 120 from said boiler and the water pressure discharged by said pump, a lever connecting said pistons and the stem of said throttle-valve, a piston exposed to the water pressure 125 from said pump and pivotally supporting 130

said lever, and a spring acting upon the pivot of said lever in opposition to said last-named piston, substantially as described.

12. In a regulator, the combination with a valve, of a lever for operating the same, a movable fulcrum for the lever, a piston arranged to move said lever upon said fulcrum, a second piston arranged to support said fulcrum, and sources of fluid pressure arranged to act upon said pistons to control the operation of said valve.

13. In a regulator, the combination with a valve, of a pivoted lever for operating the same, automatic means for shifting said lever to move the valve to either of its alternative positions, and a movable fulcrum for said lever adapted when moved away from its normal position to prevent an effective change in position of said lever.

14. The combination with a feed pump, 20 of a motor for driving the same, a regulator having a pivoted lever and means controlled thereby for causing the motor to run or to stop, automatic means for shifting said lever, and means controlled by the fall of the discharge pressure of said pump for shifting the regulator to stop said motor.

15. The combination with a feed pump, of a motor for driving the same, a regulator for said motor having a movable controlling 30 part, and means controlled by an abnormal fall of the discharge pressure from said pump, adapted to shift said controlling part to a position to stop said motor.

AUGUSTE CAMILLE EDMOND RATEAU.
